UNITED STATES PATENT OFFICE.

JAMES F. REILLY, OF PHILADELPHIA, PENNSYLVANIA.

TROLLEY FOR TRENCH MACHINES AND THE LIKE.

Application filed August 24, 1921. Serial No. 495,060.

To all whom it may concern:

Be it known that I, JAMES F. REILLY, a citizen of the United States, residing at Philadelphia, in the county of Philadelphia and State of Pennsylvania, have invented 5 certain new and useful Improvements in Trolleys for Trench Machines and the like, of which the following is a specification.

My invention relates to trolleys for trench 10 machines and the like, that is to say, to traveling carriages, and the co-acting parts, for elevating and transporting the buckets used for carrying the materials in and about trench and similar engineering operations. 15 The object of my invention is to provide an improved form of trolley, or carriage, and parts co-acting therewith, adapted to be used on an overhead trackway and operated by a simple type of power unit, which apparatus will be simple and efficient in its operation, which will afford a maximum of safety for the persons engaged in and about the work, and which may be quickly and efficiently manipulated, being to a large extent automatic in its action and adapted to 20 be controlled entirely by a single operator located at the power unit.

With the foregoing object in view my invention contemplates the provision of an improved form of trolley or carriage arranged 25 to be supported from and travel on an overhead trackway, such as the lower flange of an I beam, which may, in turn, be supported in any suitable manner, said carriage being 30 provided with a suitable sheave over which the cable for elevating the bucket passes, being further provided with a pulley block through which the elevating cable also passes, and being further provided with 35 means adapted to automatically engage and support the pulley block in its elevated position while the bucket carried thereby is being transported by the trolley or carriage along the trackway, and also being provided 40 with means whereby the pulley block may be automatically released upon certain manipulations of the cables for elevating the pulley block and for transporting the same with the bucket carried thereby.

50 The nature and characteristic features of my invention will be more readily understood from the following description taken in connection with the accompanying drawings forming part hereof, in which:

55 Figure 1 is a side elevation of a trolley

or carriage embodying the main features of my present invention, with the co-acting pulley block shown suspended therefrom;

Figure 2 is an end elevation thereof;

Figure 3 is a vertical central section 60 thereof taken approximately on the line 3-3 of Fig. 2, but with the pulley block shown in its supported position within the trolley or carriage, and the positions of certain of the parts for releasing the said pulley 65 block from the carriage being shown in dotted lines;

Figure 4 is a vertical section taken approximately on the line 4-4 of Fig. 3; and

Figure 5 is a horizontal section taken approximately on the line 5-5 of Fig. 3, the 70 pulley block being omitted.

Referring to the drawings, in the particular embodiment of my invention therein shown, the trolley or carriage comprises a 75 framework 10, made up of suitable structural shapes and plates, said framework being provided with bearing blocks 11 in the upper portion thereof, which bearing blocks form a means of support for stud shafts 12 80 upon which flanged wheels 13 are journaled. The flanged wheels 13 form a means for supporting the trolley or carriage upon a suitable trackwork, which may comprise an I beam 14, upon the lower flange 15 of which 85 the wheels 13 are adapted to travel.

To one of the cross members 16 of the framework 10 there is attached, in any suitable manner, one end of a cable 17, which cable 17 thence extends downward and 90 around a pulley 18 of a pulley block 19, thence passing upward and around a sheave 20, which is journaled on a shaft 21, which shaft 21 in turn is supported by means of blocks 22 secured in any suitable manner at 95 the proper location in the framework 10 of the trolley or carriage. After passing around the sheave 20 the cable 17 extends to and is adapted to be wound upon a controllable drum of the power unit, not shown. 100 There is also attached to the trolley or carriage 10 one end of another cable 23 which also extends to and is adapted to be wound upon another controllable drum of the power unit, not shown.

105 The pulley block 19 comprises side plates 24 having on the outer faces thereof horizontally arranged bars 25, which are secured to the side plates 24 in any suitable manner. A shaft 26 is supported in the side plates 24, 110

and in the bars 25, and forms a means for journaling the pulley 18 around which the cable 17 passes, for the purpose of supporting said pulley in the lower loop thereof.

5 Between the side plates 24 there is mounted a casting 27 extending around below the pulley 18 and forming a means for properly spacing the side plates 24 with respect to each other. Mounted in the lower portions 10 of the plates 24 is a transverse bolt 28 forming a means for supporting the hook 29, upon which the buckets for handling the material in and about the work are adapted to be mounted, the hook 29 being attached to 15 the bolt 28 by means of suitable links 30 and 31. The side plates 24 and the reinforcing bars 25 are provided with extensions forming shoulders 32, which are provided to constitute a means for seating the pulley block 20 within the trolley or carriage while the same is being transported along the trackway 14. The upper portion of each of the plates 24 is provided with inclined margins 33 for a purpose to be presently explained.

25 At each of the lower corners of the framework of the trolley or carriage there is journaled a shaft 35, and near each end of each of said shafts, adjacent the side members of the framework 10 of the trolley or carriage, there are mounted brackets 36, to 30 which brackets 36 there are secured bars 37, extending transversely across the trolley or carriage, and normally resting upon and supported by bars 38 which extend across 35 and are secured to the bottom portions of the respective side members of the framework 10 of the trolley or carriage. One of the brackets 36 on each of the shafts 35 is provided with a lever arm 39 having one end 40 of a connecting rod 40 pivotally connected to its outer end. The other end of each connecting rod 40 is pivotally connected to the outer end of a lever 41, which is secured to a shaft 42 journaled in the side 45 members of the framework 10 of the trolley or carriage. The shafts 42 are also each provided, at each end thereof, with levers 43 extending inwardly, and carrying at their inner ends transversely extending rods 44, 50 which are so located as to be adapted to be encountered by the upper inclined margins 33 of the side plates 24 of the pulley block.

The bars 37, which are pivotally supported by means of the shafts 35, are normally adapted to be encountered and raised out of their normal positions by means of 55 said inclined margins 33 of the side plates 24 of the pulley block, and thereafter when the same are permitted to return to their normal positions, to form a seat for the shoulders 32, which are provided on the pulley block 19, as hereinbefore described. Each of the shafts 35 is also provided with 60 a centrally located tripping member 45 having an arm or lug 46 normally depending

downward but adapted, when the bars 37 are in their elevated positions, to be encountered by the shoulders 32 of the pulley block 19. The trolley or carriage is also provided with a member 47 so located therein as to provide a means for limiting the upward movement of the pulley block 19 within the trolley or carriage.

The operation of the apparatus may now be explained. Assuming that the pulley or carriage is in a position directly over the work at the point where a digging operation is taking place, and from which point it is necessary to transport certain materials, a bucket, (not shown), being filled with materials to be transported is connected in any desired manner to the hook 29, which has been lowered for that purpose. The cable 23 is now held taut, through the proper control of its winding drum, by the operator at the power unit, and the cable 17 is then wound upon its drum to cause the pulley block 19 to be thereby elevated until the inclined margins 33 of the side plates 24 encounter the bars 37 and cause the same to be raised a sufficient distance to permit the pulley block to pass, after which the bars 37 will fall by gravity to their normal positions, resting upon the bars 38 which are secured at the lower end of the framework 10 of the trolley or carriage. Either of the cables 23 or 17 may now be slackened off, whereupon the shoulders 32 of the pulley block will seat themselves upon the upper surfaces of the bars 37 and will be positively supported thereby. According now to whichever direction the material is to be transported one of the cables 17 or 23 will be wound upon its drum, and the other cable permitted to slack off, and the trolley or carriage will be thereby transported along the trackway 14 in one direction or the other, as the case may be. When the trolley or carriage has arrived at the point where the material is to be delivered, the bucket is either removed therefrom and replaced by an empty bucket, or if a drop-bottom bucket be used, the bottom is actuated to permit the material to be emptied therefrom.

The trolley or carriage will then be returned to the point of the digging operation by the winding of the proper cable upon its drum and the slackening off of the other cable, the pulley block being still supported within the trolley or carriage. To now release the pulley block from the trolley or carriage to thereby permit the bucket to be lowered, the cable 23 is now held taut, and the cable 17 is wound upon its drum to cause the pulley block 19 to be elevated a sufficient distance until the inclined margins 33 of the side plates 24 of the pulley block encounter the transverse rods 44 carried by the levers 43, forcing the same up-

ward, whereby the levers 41, which are carried by the shafts 42, upon which the levers 43 are mounted, will, through the intermediary of the connecting rods 40 and the levers 39, rotate the shafts 35, thereby elevating the bars 37 out of the path of the shoulders 32 of the pulley block 19. The shafts 35 which carry the bars 37 are given a sufficient angular rotation so that the bars 37 will be carried to points where the action of gravity thereon will be eliminated and the bars will then tend to remain in elevated positions. The member 47 will serve to limit the upward movement of the pulley block 19 to insure the proper actuation of the foregoing parts. The cable 17 will now be slackened off and the pulley block 19 will thereby be permitted to descend, but in so doing, the shoulders 32 after passing the elevated bars 37, will encounter the lugs 46 of the tripping members 45, which are carried by the shafts 35, and will thereby rotate said shafts a sufficient angular extent to cause the bars 37 to again fall by gravity to their normal positions, the pulley block 19 having meanwhile passed below the bars 37. The pulley block is now permitted to descend sufficiently to enable the empty bucket to be removed from the hook 29 and a filled bucket attached thereto, after which the operation may be repeated.

It will be seen that there is thus provided a simple and efficient trolley apparatus for handling the materials in and about trench and other engineering operations in which the load will be positively held while the same is being transported, thus affording a maximum of safety for the persons employed in and about the work, the arrangement being such that the pulley block will be positively supported within the trolley or carriage while being transported, and will be positively held therein, notwithstanding that either or both of the cables may be slackened off or should break while the load is being transported. Furthermore, the arrangement is such that the entire apparatus may be operated by means of a simple type of engine or other power unit having but two drums, the manipulation of which will serve to perform all of the elevating, transporting and releasing operations so that the elevating and transporting of the buckets may if desired be entirely controlled by a single operator located at the power unit.

Having thus described the nature and characteristic features of my invention, what I claim as new and desire to secure by Letters Patent is:

1. In apparatus of the character described the combination of an overhead trackway, a carriage suspended therefrom and adapted to travel upon said trackway, a controllable cable extending downward in a loop from said carriage, a pulley block suspended in

said loop of said cable, members mounted in the carriage and adapted to be moved aside by said pulley block and to then return to their normal positions to form a seat for supporting said pulley block in said carriage, means adapted to be encountered and operated by said pulley block when the same passes to a predetermined position in the carriage for moving said supporting members to positions whereby the pulley block may be permitted to pass below the same, and means actuated by the pulley block as the same descends to positively return said supporting members to their normal operative positions.

2. In apparatus of the character described the combination of an overhead trackway, a carriage suspended therefrom and adapted to travel upon said trackway, a controllable cable extending downward in a loop from said carriage, a pulley block suspended in said loop of said cables, members mounted in the carriage and adapted to be moved aside by said pulley block and to then return to their normal positions to form a seat for supporting said pulley block in said carriage, members movably mounted in said carriage arranged above said supporting members and adapted to be encountered and operated by said pulley block when the same passes to a predetermined position in the carriage, link work connected with said members for moving said supporting members to positions whereby the pulley block may be permitted to pass below the same, and means actuated by the pulley block as the same descends to return said supporting members to their normal operative positions.

3. In apparatus of the character described the combination of an overhead trackway, a carriage suspended therefrom and adapted to travel upon said trackway, a controllable cable extending downward in a loop from said carriage, a pulley block suspended in said loop of said cable, bars pivotally mounted in the carriage and adapted to be raised by said pulley block and to then return to their normal positions to form a seat for supporting said pulley block in said carriage, members movably mounted in said carriage arranged above said supporting bars and adapted to be encountered and operated by said pulley block when the same passes to a predetermined position in the carriage, link work connected with said members for moving said supporting bars to positions whereby the pulley block may be permitted to pass below the same, and means actuated by the pulley block as the same descends to return said supporting bars to their normal operative positions.

4. In apparatus of the character described the combination of an overhead trackway, a carriage suspended therefrom and adapted to travel upon said trackway, a

controllable cable extending downward in a loop from said carriage, a pulley block suspended in said loop of said cable, bars pivotally mounted in the carriage and adapted to be raised by said pulley block and to then return to their normal positions to form a seat for supporting said pulley block in said carriage, members movably mounted in said carriage arranged above said supporting bars and adapted to be encountered and operated by said pulley block when the same passes to a predetermined position in the carriage, link work connected with said members for moving said supporting bars to positions whereby the pulley block may be permitted to pass below the same, and tripping members operatively connected with said supporting bars adapted to be encountered by the pulley block as the same descends to thereby return said supporting bars to their normal operative positions.

5. In apparatus of the character described the combination of an overhead trackway, a carriage suspended therefrom and adapted to travel upon said trackway, a controllable cable extending downward in a loop from said carriage, a pulley block

suspended in said loop of said cable, said pulley block having shoulders extending therefrom, bars pivotally mounted in the carriage and adapted to be raised by said pulley block and to then return to their normal positions to form a seat for supporting said pulley block in said carriage, a stop member mounted in said carriage adapted to limit the upward movement of said pulley block in said carriage, members movably mounted in said carriage arranged above said supporting bars and adapted to be encountered and operated by said pulley block when the same passes to the uppermost position in the carriage, link work connected with said members for moving said supporting bars to positions whereby the pulley block may be permitted to pass below the same, and tripping members operatively connected with said supporting bars adapted to be encountered by the pulley block as the same descends to thereby return said supporting bars to their normal operative positions.

In testimony whereof I have hereunto signed my name.

JAMES F. REILLY.
